SPRAY DEVICE

Edward F. Delfoe and John M. Williams,
Brooklyn, N. Y.

Application May 27, 1942, Serial No. 444,757

6 Claims. (Cl. 299—93)

This invention relates to spray devices and more particularly devices of this kind commonly referred to as fire extinguishers and the object of the invention is to provide a device of this kind employing a sealed discharge end with a crank operating the device automatically releasing the seal in the rotation of the crank, and further in so constructing the walls of the tubular casing or cylinder as to provide means for insulating as well as reinforcing the same, in addition to reducing the weight of the entire device and also providing a gripping surface on the cylinder facilitating a more firm grip thereon. The novel features of the invention will be best understood from the following description when taken together with the accompanying drawing, in which certain embodiments of the invention are disclosed, and in which the separate parts are designated by suitable reference characters in each of the views, and in which:

Fig. 1 is a side and sectional view of a device made according to the invention, and

Fig. 2 is a plan view of the device, as seen in Fig. 1, with part of the construction broken away and in section.

In spray devices and particularly those commonly referred to as fire extinguishers, it has been customary to employ rather complicated mechanisms controlling the operation of the devices, and as a rule, most of the devices have been quite heavy in comparison with the size thereof and, furthermore, no precautions have been taken to reinforce the cylinders of the devices and further to insulate the devices, particularly where the same are exposed to high temperatures such for example, as hanging in direct sunlight, and still further, devices of this kind have usually employed smooth cylinders, handling of which have been difficult.

It is the purpose of our invention to first construct a device of outstanding simplicity, thus materially reducing the manufacturing cost; further to lighten the structure as much as possible by using two spaced thin wall tubes, the inner of which forms the cylinder proper and the outer a reinforcing wall, which also provides, by virtue of the corrugations therein, a gripping surface which facilitates the firmer gripping of the device; still further the spacing of the walls facilitates the insertion of an insulating medium between the walls to protect the contents of the device from excessive temperatures to which the same may be exposed. It is a still further feature of our invention to provide a device of the

class described having means normally sealing the discharge end thereof with means for automatically releasing the seal upon operating the crank employed to discharge the fluid from the device.

In the drawing 10 represents the main cylinder of the device which is in the form of a relatively thin walled tube jacketed by an outer corrugated tube 11 spaced from the tube 10, which space is preferably filled with a suitable insulation 12 to insulate the contents of the spray device from high temperatures, and also to form a cushion.

In the construction shown, the tube 10 is of greater length than the tube 11, forming upper and lower terminal ends 13 and 14, with which top and bottom caps 15 and 16 are coupled. The cap 15 may be permanently secured in position by welding, brazing or otherwise; whereas the cap 16 is detachably mounted in position to facilitate removal of the parts for repair, cleaning or other purposes.

The cap 16 has a depressed annular wall 17, in one section of which is arranged a filling plug 18, by means of which the cylinder 10 may be filled with the desired chemical or fluid to be used in the device. Centrally of the inner surface of the cap 16 is a socket 19 for supporting the lower end of a tubular screw shaft 20, the lower end of the shaft having a number of apertures 21 opening into the bore 22 of the shaft so that fluid can pass upwardly through the shaft and be discharged through the nozzle end 23 thereof.

The cap 15 is substantially in the form of an inverted cup, the walls being contracted toward the outer closed end 24 of the cup. This end has an aperture 25 therein, through which the nozzle 23 protrudes beyond the outer surface of the wall 24. Adjacent the aperture 25 is a vent aperture 26.

At one side of the cap 15 is an enlarged portion, in which is formed a radial bore or passage 27, directly above which is a large rectangular opening or slit 28. In the bore 27 is arranged bushings 29 spaced apart by a packing 30 and in these bushings is a pin or shaft 31 to the inner end of which is secured a beveled pinion 32 and mounted on the outer square end 33 is a crank 34 secured in position by a screw 35. The crank 34 has at its free end a knob or fingerpiece 36, by which the same may be rotated and projecting from the pivot end of the crank is an arm 37 having on the inner surface thereof cams 38 adapted to cooperate with an outwardly projecting finger 39 on a pawl 40.

The pawl 40 is arranged in the opening 38 and is pivoted as seen at 41. A spring 42 is employed to normally extend the pin end 39 from the cap to be engaged by the cam 38 and also to hold the pawl in engagement with a catch 43 on a cover 44.

The cover has a yoked end 45 pivoted to the cap, as seen at 46 and on the pivot 46 is a spring 47 which engages the cover and the wall 24 so that when the cover is released by the pawl 40, the spring 47 will automatically move the cover into fully opened position out of the path of the discharge nozzle 23.

Supported centrally of the cover 44 is a thimble-shaped cup 48, in which is arranged a sealing pad or disc 49 seated upon the end of the nozzle 23 by a spring 50, so that the end of the nozzle is sealed when the cover is in closed position. The cup 48 also supports a spring sealing ring or gasket 51 upon the wall 24 so as to further seal the discharge end of the nozzle and also the vent 26.

Secured to the upper end portion of the shaft 20 is another beveled pinion 52, which meshes with the pinion 32. Arranged on the shaft is a piston or plunger unit 53 employed to pressure discharge the contents of the cylinder in the movement of the plunger in the direction of the bottom cap 16.

The unit 53 comprises a sleeve portion 54 threaded to engage the screw threads 55 of the shaft 20, the sleeve including an enlarged casting portion 56 with which is coupled a packing-gland supporting sleeve 57 and this sleeve also serves to support the cup 58 of the plunger including the reinforcing inner and outer facings 59 and 60 therefor. The inner facing has angularly extending spring fingers 61 which serve to firmly support the angular flange portion 62 of the cup 58 in engagement with the wall of the cylinder 10; whereas the facing 60 has spring members 63 which serve to back up the cup 58.

The sleeve 57 forms a seat for a coil spring 64 which bears against a number of packing discs or rings 65 which collectively form the packing-gland between the piston and plunger 53 and the shaft 20. The cup part 56 and the sleeve part 57 have cooperating flanges 66 and 67 which form the support for the cup shaped piston 58. It will thus be seen that the two parts 56 and 57 collectively form the complete assemblage of the piston or plunger unit 53.

It will be understood that when the spray device is in position for use, the piston or plunger 53 will be in its raised position in the cylinder and the cylinder filled with the desired fluid or chemical. The cover 44 will be in closed position and the crank will be arranged longitudinally of the cylinder in the manner illustrated in Fig. 1. When it is desired to use the device, the cylinder is grasped in the left hand and held by this hand near the cap end 15 and the remainder of the cylinder is placed between the arm and the body of the operator; the right hand grasps the handle 36 of the crank and the crank is rotated. In a partial rotation of the crank, one of the cams 38 will engage the finger 39 to trip the pawl 30; thus releasing the cover 44 allowing it to move into open position. Continued rotation of the crank will gradually feed the plunger 53 downwardly in the cylinder and discharge the fluid through the nozzle 23. This operation will be continued until the device has served its purpose, after which the cover may be swung into closed position again sealing the nozzle and this

is done with the handle or crank in the normal position.

It will be apparent that spray devices of this kind may be made in many sizes, that is to say, from handling a small quantity of fluid to a relatively large quantity thereof and where excessive amounts of fluid are used and the device becomes quite heavy, additional supporting straps may be employed as with other spray devices commonly known in the art. In using the device as a fire extinguisher and for emergency uses, relatively small units are constructed from a half quart to two quarts of fluid. A more or less standard size for such devices has been the conventional one quart size.

However, by reason of the lightness in construction and economy in construction of our device a quart and a half size can be adapted as a standard. This will add fifty per cent more fluid to care for greater degrees of a fire emergency without adding materially to the total weight of the complete device.

In many insulations of devices under consideration, particularly when used in motor vehicles, gasoline stations and other places where the devices may come in direct contact with sunrays or exposed to the high temperatures that may prevail in a room or compartment, these high temperatures have proved to be injurious to the device or the contents thereof. To obviate this, at least to a major degree, we employ the insulated wall structure which enable such devices to withstand much higher temperatures than have heretofore been possible, without any injurious effect upon the device. It will also be apparent that the corrugated outer wall structure, in conjunction with the insulating and cushioning material, will guard to a degree against the denting of the cylinder proper which dent may interfere with successful operation of the device.

In addition to using the device as a spray device for spraying light liquids, for example, as a fire extinguisher, the device may be used for dispensing or discharging materials of various kinds including heavy bodied materials such as oils, syrups and the like.

Having fully described our invention, what we claim as new and desire to secure by Letters Patent, is:

1. A spray device comprising an elongated cylinder, a cap closing one end of the cylinder, a screw shaft arranged longitudinally of the axis of said cylinder, a plunger in threaded engagement with said shaft and movable longitudinally of the cylinder in the rotation of said shaft, means comprising a crank mounted in said cap for rotating said shaft, said shaft being tubular in form and having a nozzle discharge opening through said cap, a cover pivoted to the cap and engaging the nozzle discharge for sealing said discharge, a spring for automatically moving the cover into open position, a pawl device on the cap and operatively engaging said cover to support the cover in closed position against the action of said spring, means on said crank operatively engaging the pawl device to release said cover automatically upon rotation of the crank to discharge the contents of said cylinder, said cylinder comprising an inner straight wall tube and an outer tube having terminal ends projecting beyond the outer tube, said cap engaging one of said terminal ends, and another closure cap engaging the other terminal end.
2. A spray device comprising an elongated cylinder, a cap closing one end of the cylinder, a

75

screw shaft arranged longitudinally of the axis of said cylinder, a plunger in threaded engagement with said shaft and movable longitudinally of the cylinder in the rotation of said shaft, means comprising a crank mounted in said cap for rotating said shaft, said shaft being tubular in form and having a nozzle discharge opening through said cap, a cover pivoted to the cap and engaging the nozzle discharge for sealing said discharge, a spring for automatically moving the cover into open position, a pawl device on the cap and operatively engaging said cover to support the cover in closed position against the action of said spring, means on said crank operatively engaging the pawl device to release said cover automatically upon rotation of the crank to discharge the contents of said cylinder, said cylinder comprising an inner straight wall tube and an outer tube having corrugations extending longitudinally, said inner tube having terminal ends projecting beyond the outer tube, said cap engaging one of said terminal ends, another closure cap engaging the other terminal end, a body of insulating material between said inner and outer tubes, and said caps abutting the outer tubes and sealing said insulating material.

3. A spray device comprising an elongated cylinder, a cap closing one end of the cylinder, a screw shaft arranged longitudinally of the axis of said cylinder, a plunger in threaded engagement with said shaft and movable longitudinally of the cylinder in the rotation of said shaft, means comprising a crank mounted in said cap for rotating said shaft, said shaft being tubular in form and having a nozzle discharge opening through said cap, a cover pivoted to the cap and engaging the nozzle discharge for sealing said discharge, a spring for automatically moving the cover into open position, a pawl device on the cap and operatively engaging said cover to support the cover in closed position against the action of said spring, means on said crank operatively engaging the pawl device to release said cover automatically upon rotation of the crank to discharge the contents of said cylinder, a plurality of packings on the plunger encircling the screw

shaft, tensional means supporting the packings in engagement with said shaft, and yieldable means supporting the periphery of the plunger in firm engagement with the cylinder wall.

5. 4. In a fire extinguisher comprising an elongated cylinder having caps at opposite ends of the cylinder and means in one of the caps and operating in the cylinder for manually discharging the contents of said cylinder, said cylinder comprising an inner straight walled tube and an outer tube having corrugations extending longitudinally thereof, said inner tube having terminal ends projecting beyond both ends of the outer tube, and said caps being supported on the terminal ends of the inner tube and in abutting relation to the ends of said outer tube.

10 5. In a fire extinguisher comprising an elongated cylinder having caps at opposite ends of the cylinder and means in one of the caps and operating in the cylinder for manually discharging the contents of said cylinder, said cylinder comprising an inner straight walled tube and an outer tube having corrugations extending longitudinally thereof, said inner tube having terminal ends projecting beyond both ends of the outer tube, and said caps being supported on the terminal ends of the inner tube and in abutting relation to the ends of said outer tube.

15 6. In a fire extinguisher comprising an elongated cylinder having caps at opposite ends of the cylinder and means in one of the caps and operating in the cylinder for manually discharging the contents of said cylinder, said cylinder comprising an inner straight walled tube and an outer tube having corrugations extending longitudinally thereof, said inner tube having terminal ends projecting beyond both ends of the outer tube, and said caps being supported on the terminal ends of the inner tube and in abutting relation to the ends of said outer tube, and a body of insulating material arranged between and spacing

20 30 said inner and outer tubes.

25 7. In a fire extinguisher comprising an elongated cylinder having a controlled discharge at one end thereof, a screw shaft extending longitudinally of the casing with means at the first named end of the casing for manually rotating said shaft, a plunger having a cup shaped part in threaded engagement with said shaft, a plurality of packing discs in said part and around said shaft, means coupled with said part for tensionally supporting the discs in engagement with the shaft, and tensional means on the plunger for supporting the periphery thereof in firm engagement with the wall of said cylinder.
